STOP MOTION FOR LOOMS

Victor C. Hassold, Chestnut Hill, Pa., assignor to
Steel Heddle Manufacturing Company, Philadelphia, Pa., a corporation of Pennsylvania

Application May 23, 1934, Serial No. 727,098

1 Claim. (Cl. 139—337)

My invention relates to stop motions for looms, and relates more particularly to that type of stop motion in which an electrical circuit is employed for effecting the actuation of the knock-off mechanism which brings the loom to a stop.

The principal object of my present invention is to provide, in a loom, improved means for bringing the same to a stop whenever a warp end breaks or becomes unduly slack.

10 A further object of my invention is to provide improved means for bringing the loom to a stop whenever either end of a harness frame falls below its normal lowermost position by reason of breakage or undue stretching of the actuating straps.

15 A further object of my invention is to provide, in an electrical warp stop motion, an improved form of timing device for so controlling the circuit that the current will be supplied to the detector devices only at the proper time, that is to say, when the harness frame carrying the detector devices is in a lowered position.

With the foregoing objects in view, my invention contemplates the provision in an electrical warp stop motion of means for maintaining the actuating circuit closed after the same has been momentarily closed by detector devices.

More specifically considered, my invention contemplates an effective arrangement for efficiently utilizing the invention described and claimed in United States Letters Patent No. 1,949,747, dated March 6, 1934, to John Jacob Kaufmann, for Warp stop motion, although it should of course be understood that my invention is also applicable to warp stop motions having other forms of detector devices.

The nature and characteristic features of my invention will be more readily understood from the following description, taken in connection 40 with the accompanying drawings forming part hereof, in which:

Figure 1 is a diagrammatic view illustrating an arrangement of circuits, and the parts controlling the same and controlled thereby, embodying the main features of my present invention.

Fig. 2 is a fragmentary elevational view of the end portion of a harness frame so constructed and arranged as to form a component part of 50 my present invention, the same having shown associated therewith contact devices for establishing an electrical circuit whenever one end of the frame falls below its normal lowermost position;

55 Fig. 3 is an enlarged fragmentary elevational

view of the upper portion of one of the heddles used in the frame shown in Fig. 2, the upper supporting rod and contact bar upon which said heddles are mounted being shown in section;

Fig. 4 is a perspective view of one of the contact members which are shown in side elevation in Fig. 2;

Fig. 5 is a side elevation of a device for bringing the knock-off mechanism into action when the circuit is closed, the casing in which said device is mounted being shown in section, and the parts being shown in the positions assumed when the loom is running normally;

Fig. 6 is a front elevation of the device shown in Fig. 5, the cover plate being removed; 15

Fig. 7 is a top or plan view of the device shown in Fig. 5, the casing here also being shown in section;

Fig. 8 is a view similar to Fig. 5, but with the parts in the positions assumed when the circuit 20 is closed to bring the knock-off mechanism into play;

Fig. 9 is a side elevational view of the timing device, the shaft on which the rotating parts thereof are mounted being shown in section; 25

Fig. 10 is a front elevational view of the rotating parts of the timing device shown in Fig. 9; and

Fig. 11 is a front elevational view of the parts of the timing device which are operated upon the 30 rotating parts shown in front elevation in Fig. 10.

It will, of course, be understood that the drawings and description herein contained are illustrative merely, and that various modifications and changes may be made in the structure disclosed without departing from the spirit of my invention.

Referring now more particularly to Figs. 2, 3, and 4 of the drawings, there is there shown a loom harness frame having associated therewith a detector mechanism for establishing an electrical circuit whenever a warp end is broken or unduly slack, or whenever either end of the frame falls below its normal lowermost position by reason of a broken or stretched actuating strap or cord. 45

As there shown, the harness frame comprises top and bottom rails 15 and 16, respectively, made of wood and connected at their end portions by side struts 17, made from metallic bars. The frame is also provided with the usual upper and lower heddle supporting rods 18 the ends of which are positioned in the side struts 17 of the frame and secured therein in any preferred manner, such for example as by means of springs 20, which are mounted in the side struts 17 and 55

which have their end portions engaging suitable apertures 21 in the projecting outer ends of the heddle supporting rods 18.

The heddles 22 are preferably of the type which are made from a thin flat strip of metal or wire. Each of the heddles is provided with the usual central warp eye 23, through which an individual warp end 24 extends, and with a mortise or slot 25 near each end thereof for mounting the heddle on the supporting rods 18. The slots or mortises 25 are elongated so as to permit relative vertical movement of the heddles with respect to the frame and the supporting rods.

Each of the heddles 22 is also provided with an additional slot 26 through which a contact bar 27 extends. The contact bar comprises a central metallic strip 28 mounted in an enclosing metallic envelope 29, U-shaped in cross section. The central metallic strip 28 is insulated from the envelope 29 by means of a strip 30 of insulating material, also U-shaped in cross section. The upper edge of the central metallic strip 28 projects above the upper edge of the enclosing envelope 29.

The ends of the contact bar 27 are mounted in the side struts 17 of the frame in suitable slots therein, so shaped as to permit said contact bar to have a range of vertical movement with respect to the frame, whereby the same may be raised and lowered when the frame is actuated, for a purpose and in a manner to be hereinafter more fully set forth.

The upper end of the slot 26 in each heddle, through which the contact bar 27 extends, is preferably provided with an inclined marginal edge 31, also for a purpose to be hereinafter more fully set forth.

The central metallic strip 28 of the contact bar extends at one end beyond the end of the enclosing envelope 29 thereof, where it is notched as at 32, the notch 32 being engaged by the eye bolt 33. The eye bolt 33 is normally under the tension of a spring 34, which holds the same in engagement with the notched end 32 of the central metallic strip 28, thus serving as a means of preventing longitudinal movement of the contact bar 27 in the frame, and also as a means of maintaining the same in the electrical circuit. The eye bolt 33 and the spring 34 are carried by a suitably shaped piece 35 of insulating material, mounted on the end strut 17 of the frame.

The spring 34, which imparts the tension to the eye bolt 33, is connected at its lower end to a bolt 36, which also serves as a means for attaching one end of a wire 37. The wire 37 extends downwardly, within a protecting tube 38, along the outside of the end strut 17, terminating at its lower end within a block 39 of insulating material, where it is electrically connected, by means of an eye bolt 40, to one end of a coil spring 41, to which the current is periodically supplied, as will be hereinafter more fully set forth.

The enclosing envelope 29 of the contact bar 27 makes an electrical connection with the end strut 17 where it passes through the slot thereof, and this end strut 17 is grounded by means of a coil spring 42, one end of which is attached by means of an eye bolt 43, to the bent over extension 44 of the side strut 17 at the lower end of the harness frame.

It will be seen that the grounding of the end strut 17 by means of the coil spring 42 serves to ground the heddle supporting rods 18, the heddles 22, and the side strut 17 at the other end 75 of the frame, as all of these parts are normally

in electrical connection with each other by reason of the metallic contacts existing therebetween.

An arm 50, made from a metallic bar, extends outwardly from each of the side struts 17 to which it is secured. The arm 50 is electrically connected to the end strut 17 at the point where it is secured thereto.

At each end of a set of harness frames in a loom, there is mounted a contact member 51 comprising a bar having a horizontal upper edge. The contact members 51 are so positioned that in the event that one of the actuating straps or cords (not shown) of the harness frame should break or become unduly slack, and either end of 10 the harness frame should fall below its normal lowermost position, the arm 50 carried at that end of the frame will come in contact with the upper horizontal edge of the contact member 51. The arms 50, in the normal operation of the 20 loom, do not come in contact with the upper horizontal edges of said contact members.

For supporting the contact members 51 in proper position, each of said members is provided with a lug portion 52, by means of which it is mounted on the upper end of a vertical standard 53. The fastening nuts 54, however, are suitably insulated from the lug 52 by means of insulating washers 55, and an insulating bushing 56 serves to insulate the standard 53 from said lug. The 30 lug 52 of the contact member 51 is provided with a screw 57 for the attachment of a wire, by means of which the member 51 is included in an electrical circuit, as will be hereinafter more fully set forth.

For the purpose of insuring that the current will be supplied to the detector parts at such time only as the harness frame is in its lowered position, there is provided a timing device, shown in detached detail in Figs. 9 to 11 of the drawings. 40

The timing device as shown consists of a pair of flat spring members 60 and 61 held in parallel relationship by means of an interposed block 62 of insulating material at the rear ends thereof, the front ends of the springs 60 and 61 being 45 free to be flexed in a manner to be presently described. The spring members 60 and 61 are also provided at their rear ends with binding posts 63 and 64, respectively, and nuts 65 threaded thereon for attaching the circuit wires thereto. 50

The spring members 60 and 61 are mounted in a channeled block 66, being held in position therein by means of a bolt 67. The spring members are insulated from the bolt by means of a bushing 68, and are insulated from the channeled block in which they are mounted by means of suitably shaped saddle pieces 69 of insulating material. The channeled block 66 has a vertically extending standard 70, by means of which it may be mounted in a suitable bracket (not shown) 60 of any preferred design.

The free ends of the springs 60 and 61, are brought into contact with each other at the proper times by means of rollers 71, made of insulating material. The rollers 71 are journaled in 65 bracket members 72 which are clamped to one of the rotating shafts 73 of the loom. The bracket members 72 are preferably made of sheet metal, suitably shaped so that each of said members will be provided with two side portions 74. 70

The side portions 74 of the bracket members 72 are V-shaped, so that the inner margins 75 thereof will readily accommodate themselves to various sizes of shafts found in different looms. The ends of the arms of each V-shaped side portion 74 75

of each bracket member 72 are connected by bridge portions 76, through which the clamping bolts 77 extend. The clamping bolts 77 are provided with nuts 78 which are seated between the side portions 74 of the brackets 72.

It will thus be seen that the actuating rollers 71 of the timing device may be readily adjusted to their proper positions on the shaft, so that as the shaft rotates, said rollers 71 will be brought 10 at the proper time to bear against the free end of the upper spring member 60, flexing the same until it contacts with the lower spring member 61, thereby completing the circuit at this point.

The device for bringing the knock-off mechanism into play, and for maintaining the actuating circuit closed after the same has been momentarily closed by the detector devices, is shown in Figs. 5 to 8 of the drawings. As there shown, the device is mounted in a casing 80, having a 20 movable cover 81 on the front thereof to permit access to the interior parts for the purpose of effecting the necessary adjustments.

Binding posts 82 and 83 are secured to the casing 80, being suitably insulated therefrom in 25 the usual manner. The binding posts serve to connect the line wires of the circuit to the device.

A bracket 84 is secured to the rear wall of the casing 80, said bracket having secured thereto an extending arm 85 which serves to support 30 the coil 86 of an electromagnetic. An armature 87 is pivotally connected to lugs 88 extending from the bracket member 84, by means of pivot screws 89. A spring 90 tends to impel the armature 87 to the normal inoperative position, which position is determined by means of an adjusting screw 91 mounted in the armature 87. The head of the screw 91 bears against an extension 92 of the bracket member 84 when the armature 87 is in its normal inoperative position.

40 The armature 87 carries a downwardly extending arm 93, the lower end of which is bent over, as at 94, and provided with a suitable perforation 95 for the connection thereto of the wire or rod 96 which serves to raise the dagger 97 of the shift lever operating mechanism, as will be hereinafter more fully set forth.

The upper pole piece 98 of the electromagnet extends through the bracket arm 85, projecting above the upper surface thereof. An armature 50 99 is arranged in proximity to the upper pole piece 98, this armature being carried on the free end of a relatively light leaf spring 100, which in turn is supported on an insulating block 101 at the rear end of the projecting arm 85 of the bracket member 84. The armature 99 is normally held away from the pole piece 98 of the magnet by the tension of the spring 100, being limited in its movement away from said pole piece by means of an adjusting screw 102 threaded in the casing 80.

The armature 99 is arranged in a shunt circuit line, the arrangement being such that when the coil 55 56 is energized the circuit will be completed through the armature 99 and the pole piece 98, as will be hereinafter more fully set forth. The purpose of the foregoing arrangement is to provide a relatively sensitive and quick acting means for completing the circuit through the coil 86, and for maintaining the same after a momentary contact is established by the detector parts carried by the harness frame.

70 Referring now more particularly to Fig. 1 of the drawings, there is there shown a typical arrangement of circuits, and the parts controlling the same and controlled thereby, in connection

with which the devices shown in Figs. 2 to 11 of the drawings are adaptable for use, although it will of course be understood that various modifications in the arrangement of the circuits may be made, to meet the varying conditions found 5 in practice.

As there shown, 103 represents a source of electrical energy, such for example as a battery, one terminal of which is connected by line 104 to a ground as indicated at 105. The other terminal 10 of the battery 103 is connected by line 106 to a stationary contact member 107 mounted upon, but suitably insulated from, a portion of the loom frame (not shown) adjacent the knock-off lever.

15 The knock-off lever 108 carries a spring arm 109, adapted in the normal operation of the loom to engage the contact member 107. The spring arm 109 is insulated from the knock-off lever 108, and is connected by line 110 to one end of the coil 20 86 of the electromagnetic device shown in Figs. 5 to 8 of the drawings, and hereinbefore described.

The other end of the coil 86 is connected by line 111 to one of the binding posts 64 of the timing device shown in Figs. 9 to 11 of the drawings, and hereinbefore described in detail. The other binding post 63 of the timing device is connected by line 112 to the lower end of the coil spring 41, which is electrically connected, by the several 30 parts hereinbefore set forth, to the central metallic strip 28 of the contact bar 27. The other coil spring 42, which is electrically connected to the side struts 47, heddle supporting rods 48, and heddles 22 of the frame, is connected by line 113 35 to a ground as indicated at 114.

A shunt line 115 extends from line 111 to the spring 109 which supports the armature 99 at the top of the electromagnetic device hereinbefore described, the pole piece 98 of this electromagnetic device being grounded as indicated by line 116 and ground 117, so that when the coil 86 is energized and the armature 99 contacts with the pole piece 98, an alternative path for the current is provided, for a purpose to be hereinafter more 40 45 fully set forth.

Shunt lines 118 are connected to lines 111. These shunt lines 118 extend to the bars 51, hereinbefore described, which are mounted at the sides of the heddle frames.

The rod 96, which is connected at its upper end to the arm 93 carried by the armature 87 of the electromagnetic device, is connected at its lower end to the dagger 97 which is carried by the shipper rod 119, the arrangement being such that 55 when the dagger 97 is raised it will be engaged by a lug 120 carried by the lay 121, and thereby cause the shipper rod 119 to be actuated by the movement of the lay whenever the core 36 of the electromagnet is energized. The shipper rod 119 60 also carries a lug 122, which is adapted to engage and actuate the knock-off lever 108 when said shipper rod 119 is thus actuated.

The operation of the device may now be explained. It may first be pointed out that when 65 the loom is functioning normally, the knock-off lever 108 will be in such position that the spring arm 109 carried thereby will be in contact with the member 107, whereby, if the circuit be otherwise established, the current will be supplied 70 from the battery 103, or other source of energy, to the coil 86 of the electromagnetic device.

When, however, the knock-off lever 108 is in the position assumed when the loom is stopped, the spring arm 109 will be separated from the 75

contact member 107, thereby maintaining the circuit open whenever the loom is not operating. When the loom is functioning normally, the circuit will be open at the harness frame, but in the event of certain contingencies a number of alternative paths for the current are provided, as will hereinafter appear.

When a harness frame descends to its lowermost position, the tension imparted by the warp ends 24 controlled by the heddles 22 in said frame will cause the entire set of heddles therein to be raised, this action being permitted by reason of the elongation of the slots 25 in the heddles. However, the lower end of the slot 26 of each heddle is so located in the length of the heddle that it will engage the contact bar 27, and the entire set of heddles in a frame will elevate said contact bar with respect to the frame as the frame descends.

In this manner, the contact bar 27 will be brought to such position in the frame that in the event of one of the heddles 22 falling with respect to the frame, by reason of the warp end 24 controlled thereby being broken or unduly slack, the inclined marginal edge 31 at the upper end of the slot 26 of said heddle will contact with the central metallic strip 28 of the contact bar.

Meanwhile, the shaft 73 of the loom is rotated to a point where one of the rollers 74 will have been brought into engagement with the spring 60 of the timing device, flexing the same until it contacts with the lower spring 61 of said timing device.

Current will then flow from the battery 103, or other source of electrical energy, through line 106 to contact member 107, thence through spring arm 109 and line 110 to the coil 86 of the electromagnetic device, causing the same to be energized. The current, after passing through the coil 86, passes by line 111 to the binding post 64 carried by the lower spring 61 of the timing device, thence through said springs 61 and 60, to binding post 63, thence by line 112, through coil spring 41 to wire 37, thence through bolt 36, spring 34, 45 and eye bolt 33, to the central metallic strip 28 of the contact bar 27.

Current then passes from the central metallic strip 28 of the contact bar, through the dropped heddle 22, thence through the heddle supporting rods 18 and one of the metallic side struts 17 of the frame, thence through eye bolt 43, coil spring 42, and line 113, to ground 114, it of course being understood that as one of the terminals of the battery 103 is grounded by line 104 and ground 105, the circuit will thus be completed.

It will be seen, however, that as the contact made by the timing device is of but momentary duration, and that as the frame rises the contact established by the dropped heddle 22 with the central metallic strip 28 of the contact bar 27 will also be broken, it is desirable that means be provided for maintaining the energization of the coil 86. For this purpose, the auxiliary armature 99 is provided, which is relatively light in weight, and is supported by a sensitive spring 100. Hence, as soon as the circuit is established as above set forth, the armature 99 will be attracted to the pole piece 98 of the magnet, making an electrical contact between the armature 99 and the pole piece 98. The current, after passing through the magnet, will then pass from line 111, by means of line 115, to the armature 99, thence through the

pole piece 98, which is grounded as indicated by line 116 and ground 117.

Whenever the coil 86 is energized, the armature 99 will be attracted toward the lower pole piece thereof, causing the rod 96 to raise the dagger 97 which is carried by the shipper rod 119. When the dagger 97 is thus held in its raised position, it will be encountered by the lug 120 carried by the lay, so that as the lay moves, the shipper rod 119 will be actuated, and the lug 122 carried by said shipper rod will engage the knock-off lever 108, causing the same to be brought to a position to stop the loom. When the knock-off lever 108 is thus actuated, the spring arm 109 carried thereby will be brought out of contact with the contact member 107, so that the circuit will thereafter remain open until the broken or slack warp end is tied up or adjusted, as the case may be, and the loom is again started by the operator.

It will also be seen that whenever one end of the harness frame falls below its normal lowermost position, the coil 86 of the electromagnet will be energized, the current in this instance passing from line 111, through one or the other of the shunt lines 118 (depending on which end of the frame has dropped), to the contact member 54, thence passing through arm 53, thence to the metallic end strut 17 of the frame, through coil spring 42, and line 113 to ground 114.

By the arrangement hereinbefore described, there is provided a warp stop motion in which the establishment and maintenance of the circuit, until the knock-off mechanism is brought into play, will be insured, but in which accidental stoppage of the loom, by reason of the closing of the circuit during the period in which the harness frame is being raised and lowered, will be reduced to a minimum.

The arrangement is such that a single timing device may, if desired, be used for a plurality of harness frames.

Furthermore, the arrangement is such that in the event of the actuating cords or straps of the harness frame becoming broken or stretched, the loom will be automatically stopped, and this without undue complication of the circuit or circuits employed.

I claim:

In an electrical stop motion for looms the combination with a loom harness including a harness frame, warp shedding heddles, means for supporting said heddles in the frame, a contact bar mounted in the upper portion of the frame so as to have a range of vertical movement with respect thereto and adapted to be moved to its operative position when the frame is lowered, each of the heddles having a portion normally free of engagement with the contact bar but adapted to contact therewith to establish an electrical circuit when the warp end controlled by said heddle is broken or unduly slack, of a timing device for said circuit adapted to maintain said circuit open except when the harness frame is in its lowered position, an electromagnet controlled by the circuit, an armature operable by said electromagnet, mechanism controlled by said armature for stopping the loom, an auxiliary armature operable by said electromagnet, and means controlled by said auxiliary armature for maintaining the energization of said electromagnet after its initial energization.

VICTOR C. HASSOLD.
